INVENTOR.

UNITED STATES PATENT OFFICE.

ALEXANDER B. SIMPSON, OF JERSEY CITY, NEW JERSEY.

ELECTRICAL INSULATOR.

1,258,051.

Specification of Letters Patent. Patented Mar. 5, 1918.

Application filed April 21, 1914. Serial No. 833,454.

To all whom it may concern:

Be it known that I, ALEXANDER B. SIMPSON, a citizen of the United States, residing at Jersey City, county of Hudson, State of New Jersey, have invented certain new and useful Improvements in Electrical Insulators, of which the following is a specification, the accompanying drawings forming part of the same.

10 The main object of my invention is to simplify, cheapen, and expedite the means of insulating the joint interconnecting a plurality of wires in electrical contact.

In insulating the joints of electric wires, 15 the time required to wrap the insulating tapes around the joint is very great, and the soiling of the hands and surrounding objects are often matters of serious expense.

My improvement consists in the peculiar 20 construction of a hollow tube insulator having screws to clamp the insulation of the group of interconnected wires.

In order that my invention may be fully understood I shall first describe in detail the 25 mode in which it is carried into practice, and then distinctly claim the invention.

Reference is made to the accompanying 30 drawings forming a part of this specification, in which like parts are designated by the same numbers or letters in all the figures.

Figure 1 is a sectional view of my insulator secured to a large group of interconnected wires. Fig. 2, is a view of the wire receiving end opening. Fig. 3, is a sectional 35 view of my insulator. Fig. 4 is a side view of the same figure.

In Fig. 1, the insulated wires are shown connected together by a binding screw device and the insulator consists of the hollow 40 tube, designated by letter B, of porcelain, vulcanized fiber or other hard insulating substance, and the two screws of corresponding insulating substance, designated by letter A, are threaded and fit loosely in the threaded holes O and O respectively, to form a space between the screws for the joint, designated by letter C. To increase the scope 45 of the clamping screws A, A, to follow any variation in the bulk of the insulations to be clamped the screws A, A are each made to

screw into the body B as far as the radii center point line of the bore N, by continuing the threading of the openings O, O on the inner sides of the bore N, so as to engage the threading of the screws A, A as far as the 55 center point line of the bore N. On screwing in or screwing out the screws, A and A, the wireway is diminished or enlarged at will.

The wires which may be of different characteristics and sizes are grouped into two sets nearly alike in bulk, making a set for each end of the insulator; one group is passed through the tube by way of the openings, designated by letter O, and all the 60 wires are then connected together by soldering or clamping, after which the insulator is moved to cover the joint C; by screwing in the screws A and A, the insulations of the varicus wires are forced close together and 65 tight against the wall of the tube, and clamped securely in position.

It is evident that the shape of the tube is not confined to the form shown but may be square or other shape without departing 70 from the boundaries of my invention.

I claim as my invention:

An insulator of hard insulating material, consisting of a hollow tube with open ends, a threaded screw opening in the wall of the 80 tube close to each end, and at right angles with and of the same diameter as the bore of the tube, the threading being continued through the wall on the inner surface of the bore to a depth of half the diameter of the 85 bore, a headless screw of hard insulating material, having a flat top and a flat tip, fitted loosely in each of the threaded openings, to clamp a group of wires passed through the insulator, between the screw tips and the 90 inner surface of the tube.

Signed at Jersey City in the county of Hudson and State of New Jersey this sixth day of April A. D. one thousand, nine hundred and fourteen.

ALEXANDER B. SIMPSON.
